CARBON PILE DEVICE

Thomas W. Moore, Dayton, Ohio, assignor, by
mesne assignments, to American Machine &
Foundry Company, New York, N. Y., a corpora-
tion of New Jersey

Application April 10, 1951, Serial No. 220,290

25 Claims. (Cl. 201—51)

1

This invention relates to carbon pile devices and to electromagnetic means for effecting actuation thereof.

It is the principal object of the invention to provide an electromagnetically actuated carbon pile device which is simple and economical in construction, which can be readily assembled and which will provide operating characteristics that are uniform and readily adjustable, and which will maintain a high degree of accuracy and uniformity in operation even though subjected to severe jolts or mechanical shocks and notwithstanding wide changes in temperature.

It is a further object to provide an electromagnetic device having an armature and a pole piece which are accurately located relative to each other for high reliability and uniformity throughout operation.

It is a further object to provide a core and pole piece assembly for an electromagnetic device in which the pole piece comprises two portions of magnetic material spaced from each other to form a non-magnetic gap with the entire surface thereof plane and highly uniform and in accurate normal relation to the axis of the core.

It is also an object to provide a simple and highly satisfactory method of forming such a core and pole piece assembly.

Other objects and advantages will be apparent from the following description, the accompanying drawings and the appended claims.

In the drawings—

Fig. 1 is a view partially in section and partially in elevation of an electromagnetically operated carbon pile device constructed in accordance with the present invention;

Fig. 2 is a horizontal sectional view on the line 2—2 of Fig. 1 with the solenoid shown in elevation;

Fig. 3 is a horizontal sectional view of Fig. 1 through the pile and radiator on the line 3—3 of Fig. 1;

Fig. 4 is a vertical sectional view on an enlarged scale of the electromagnetic part of the device with parts broken away to further show the construction;

Fig. 5 is a top plan view of the armature with parts broken away;

Fig. 6 is a detailed broken sectional view showing the hinge construction and the parts which limit the travel of the armature on line 6—6 of Fig. 5;

Fig. 7 is a detail view of the means for adjusting the initial pressure on the carbon pile;

Fig. 8 is an exploded perspective view of the parts forming the armature assembly;

2

Fig. 9 is a vertical sectional view on an enlarged scale through the lower portion of the pile and radiator, further showing the lower contact assembly;

5 Figs. 10 through 12 are vertical sectional views showing the steps in the construction of the pole piece and core assembly;

Fig. 13 is a plan view of the face of the pole piece;

10 Fig. 14 is a bottom view of the lower contact assembly;

Fig. 15 is a detail sectional view on the line 15—15 of Fig. 14; and

15 Fig. 16 is a top plan view of the lower contact assembly.

Referring to the drawings which show a preferred embodiment of the invention, the carbon pile is shown generally at 10 consisting of a series of relatively thin disks of carbon, preferably having a central aperture therein, which are stacked in a tubular member 12 of ceramic or like material having proper strength and capable of operation at elevated temperature. A suitable ceramic material for this purpose is that known as Steatite, although other comparable materials may likewise be used. The tube is of the proper internal diameter to receive the carbon disks freely therein and the stack is of such length as to leave a projecting portion of the ceramic tube at either end thereof.

20 In order to dissipate heat from the pile which develops in the carbon disks in operation, a radiator 15 in the form of a cylindrical structure is provided, and to increase the radiating effect, the device is finned as shown at 16. As illustrated in Fig. 9, the fins are of stepped width, there being a narrower internal cut-out 17 with a wider outer portion 18 forming such steps. These fins are preferably formed by turning a solid bar of the material in a lathe and performing two cuts, the inner and deeper one being narrower than the outer cut, thereby making possible the formation of such deep cuts and maintaining good heat transfer and physical strength characteristics throughout. A suitable material for the radiator is one which has good heat conducting qualities, and where weight is a factor, both properties are well provided by the use of aluminum.

25 In order to provide for expansion and contraction of the radiator, and to maintain the same in close heat transferring relation with the ceramic tube throughout such temperature changes the radiator is provided with an axial cut shown at 20 which extends throughout its length. The internal bore of the radiator is such that it normally must be spread in order to be

received over the ceramic tube 12, and when so positioned it grips the tube due to its resiliency and thus is in close heat transferring contact therewith. As the diameter of the tube changes under variations of temperature, the radiator body expands or contracts sufficiently to remain in such gripping contact, and thus there is no decrease in the heat conducting properties thereof as the dimensions of the tube increase or decrease.

Electric contact is made with the lower end of the pile by an insulated contact assembly 25 shown in Figs. 9 and 14 through 16. The contact itself is in the form of a thin lamination of silver 26 mounted upon a backing 27 of Monel metal, which in turn is secured to a contact element 28 having a lug 29 extending outwardly therefrom. The assembly is carried by an insulating plate 30 of laminated silicon fiber glass or the like, the entire structure being secured by means of a central rivet 32 having a spring washer 33 on the lower face of the insulating member to retain the assembled structure together. It will be seen that the head of the rivet 32 is located in the central aperture of the carbon disks with the face of the disks seating directly upon the contact surface 26 and thus good electrical contact is maintained. A prong 34 may be struck into an aperture in the insulating plate to prevent twisting therebetween after assembly.

The insulating plate 30 is seated in a cover plate 35 of suitable material such as stainless steel, being mounted diagonally therein as shown in Figs. 14 and 16 in an offset portion 36 and secured therein by a pair of rivets 37. The cover plate is held in place by four studs 38 having nuts 39 by means of which the cover plate is secured in position with the contact member 28 being drawn against the lower end of the ceramic sleeve 12 to properly locate the lower contact assembly.

In order to secure accuracy of control with such a device it is important that the pole piece of the electromagnet be positioned with accuracy relative to the core and also relative to the armature, so that the movements of the armature will take place uniformly and with the air gap being substantially uniform in all relative positions thereof. It is also important that the magnetic parts of the structure, which are usually formed of iron subject to rapid rusting and corrosion, be plated for use, and that such plating operation not interfere with proper accuracy of alignment or result in introduction of non-uniform and disturbing factors into the operating characteristics. In accordance with the present invention, therefore, the pole piece is constructed in accordance with the steps indicated in Figs. 10 through 13. Referring first to Fig. 10, a body of magnetic material 40 in the form of a flat plate is formed with an annular groove 41 on one face having a tapered or conical section as shown, and with a tapered aperture 42 having its larger width on the opposite face. It should be particularly noted that the groove 41 extends only partially through the body from the face thereof, leaving an integral section 43 on the opposite face.

A core member 45 is provided with a central bore 46 and located in position on the grooved face of the body 40, centrally thereof, as indicated in Fig. 11. It is secured thereto in suitable manner such as by brazing, indicated at 47

in a position substantially normal to the opposite or working face of the pole piece 40.

Non-magnetic material 50 is introduced into the groove 41 partially filling the same and bonding firmly to the side walls of the grooves. A suitable material for this purpose is a ring of brazing material, and such material may likewise be used to bond the core 45 in position upon the face of member 40 and thus both operations may be performed at the same time.

Thereafter the assembly is suitably supported by means of the core 45 and material is removed from the working face of the body 40 to a depth such as to cut through the integral section 43 and into the body of non-magnetic material 50. It will be seen that by removing more material from the surface, the non-magnetic gaps indicated at 52 are increased in width, and vice versa, while at all times assuring that the surface which will form the actual pole face is plain, flat, and accurately normal to the axis of the core. This operation is conveniently accomplished by chucking the core in a lathe and cutting across the face of member 40 to the required depth as indicated in Fig. 12. The finished piece then has the appearance in plan as shown in Fig. 13 with an annular gap 52 of non-magnetic material separating the two magnetic portions and retaining them permanently in flat and plane relation to each other.

The pole face and core assembly is then assembled with the solenoid indicated at 60 and a bottom magnetic plate 62 is fitted over the end of the core as shown in Fig. 4. It is preferred to have a close fit with the core projecting beyond the lower face of the plate 62 as shown at 64 and capable of relative sliding movement through the plate, although with as small an air gap as possible. Thus assembly is facilitated and likewise some axial movement is permitted between these parts in response to thermal expansion and contraction but without materially increasing the reluctance of the magnetic circuit.

The magnetic structure is completed by means of a series of posts 65, held in assembled relation upon the lower magnetic plate 62 by means of threaded extensions 66 formed as part of the studs 38. As shown in Fig. 4 the posts are bored and tapped to receive the threaded ends 66 and the remaining section of magnetic material is such as to provide substantially uniform flux density throughout the magnetic circuit. The posts 65 are preferably ground accurately to uniform length and thus the upper ends when mounted upon the plate 62 are all accurately in the same plane and adapted to engage with and to support pole piece 40 in accurate relation thereto.

The pole piece is held in place upon the posts 65 by means of two pairs of bolts, an outer pair 70 carrying collars 72, and an inner pair 74 likewise having collars 75 thereon.

The armature assembly is composed of flat plate-like members which may be readily manufactured in flat condition and subjected to suitable heat treating to assure the absence of distortions or strains, so that the assembly will maintain its flat characteristic notwithstanding changes in temperature and the like during use. The assembly comprises the armature plate 80 which is of generally corresponding dimensions with pole piece 40, having notched out areas 81 at the forward end thereof which are adapted to fit under the headed part of collars 72, as

shown in Fig. 6, the latter forming limit stops to prevent excessive travel of the armature. Plate 80 has a part 82 extending rearwardly beyond the pole piece 40 and a thin sheet metal hinge spring 85 is secured to the lower face of this portion of the armature plate, such hinge 85 having forwardly extending projections or ears 86 apertured at 87 to be received over the rearward pair of studs 74. The armature plate 80 is notched out as shown at 88 to provide clearance for these forwardly projecting portions 86. Also as shown in Fig. 6, collars 75 are adapted to seat downwardly upon the face of projections 86 so that when the rear bolts 74 are tightened, the hinge spring 85 is secured in direct position upon the flat face of the pole piece 40. Also as shown the hinge member 85 is relatively thin and thus the lower face of the armature 80 is substantially parallel to but spaced slightly away from the face of pole piece 40.

The spring hinge 85 is secured to the armature plate 80 together with an upper flat weight 90 and a lower flat weight 91, rivets 92 securing all such parts together. The weights are of such size and location as to counter-balance the mass of the armature about its hinge and thus to compensate for such shocks or vibrations as may occur in the plane normal to the face of the armature. It will also be noted by reference to Figs. 4 and 5 that the hinge for the armature is actually formed by the two spaced projecting portions 86 of the hinge plate immediately adjacent the studs 74, and located substantially at the rear edge of the pole piece which thus forms a fulcrum for the armature. Except for the extensions 86, the hinge plate terminates along a line which falls beyond the edge of the pole piece and thus assures that the pivoting of the armature will take place about the two extensions of the spring and substantially in the plane of the cover plate itself. Movement of the armature assembly is controlled at all times and it is assured that such movement will take place with the armature plate 80 maintaining uniform clearance from the pole piece, throughout its range of movement.

In order to provide a predetermined minimum pressure on the carbon pile sufficient to prevent separation of the disks and burning under minimum or no magnetic pull, a spring device is provided by means of which this minimum pressure condition may be adjustably established and maintained. For this purpose a groove 100 is formed in the upper surface of armature plate 80, this groove being preferably arcuate in cross section as illustrated in Fig. 4. At its deepest point it closely approaches the lower face of the plate so that the force applied thereto will, as nearly as practicable, be effective in the same plane as that of the hinge means. The spring itself is in the form of a clip 102 having slotted openings 103 at either end which are adapted to be received over the pair of studs 74 above collars 75. A central downwardly bent portion 104 has a depressed tongue 105 the tongue being in direct bearing engagement with the curved bottom surface of the groove. It will be seen that the force applied by this spring is in the direction to cause compression of the pile and that by shifting the clip on its supporting studs 70 the moment arm of that force can be varied, to thereby change the initial or minimum pressure condition. The arrangement of the parts as shown, including the angle of the tongue 105 and the arcuate surface of the groove 100 also con-

tribute to maintenance of substantially uniform conditions compensating largely for any change in the effective force applied as a result of the travel of the armature plate.

5 Electrical contact is made and pressure applied to the top of the pile by means of a screw 110 which is threaded into an aperture in the center of the armature plate with a spring clip 111 (Fig. 7) welded or fastened thereto which has friction portions 112 engageable on the surface of the armature plate and which tend to retain the screw frictionally in any adjusted position. In response to turning, the screw is raised or lowered with respect to the armature plate.

10 The lower end of the screw is cupped and the surface of the cup preferably coated with a good electrical conductor such as silver for receiving the upper end of a push rod 115, preferably of beryllium copper and the like and having a similar silver contact to establish good electrical conductivity. The push rod 115 extends through the central aperture 46 of the core and projects from the lower end thereof where a pressure contact 117 is fastened, in the form of a silver contact disk 118 with a Monel backing disk 119. In this way operating pressure is transmitted to the top of the pile, the pull of the solenoid thus being utilized to apply pressure to the pile to cause a lowering of the electrical resistance 30 thereof.

20 A dust cap 120 is preferably clipped over the upper portion of the device, covering the armature assembly, and the posts 65 may be suitably drilled as shown at 121 to serve to receive a 35 mounting structure 122 thereon by means of which the control may be mounted and the opposite or grounded electrical connection made thereto.

25 In the construction of the device the parts of 40 the magnetic circuit are preferably first formed accurately as to size and shape, the posts 65 being accurately ground or otherwise formed to uniform length and the flat parts of the pole piece and armature assembly suitably heat treated under stacking and pressure in order to assure annealing in a flat condition. Thereafter, and before assembly into final form, the parts 50 may be electroplated in order to protect them against rusting and the like, such electroplating not resulting in any distortion or deformation of the parts. When assembled following such plating, the parts retain their flat and accurately formed relationship, both as initially assembled, and during changes of temperature, rapid or 55 severe shocks and the like, to which the device may be subjected in use. Highly satisfactory results have been obtained over a complete range of operating temperatures and over shock and vibration conditions up to many times the force 60 of gravity.

While the method and form of apparatus herein described constitute preferred embodiments of the invention, it is to be understood that the invention is not limited to this precise method and form of apparatus, and that changes may be made therein without departing from the scope of the invention which is defined in the appended claims.

65 What is claimed is:

70 1. A carbon pile device comprising a solenoid, an armature for said solenoid, a carbon pile, means for transmitting pressure from said armature to effect compression of said carbon pile, a tubular member for receiving said carbon pile inwardly thereof, and a metallic radiator of re-

silent construction having an internal diameter normally less than that of said tubular member surrounding said tubular member in close heat transferring relation therewith, said radiator having a longitudinally extending slot therein and being expandable to receive said tubular member and to maintain said close heat transferring contact with said tubular member under temperature changes.

2. A carbon pile regulator comprising a solenoid, an armature for said solenoid, a carbon pile, means for transmitting pressure from said armature to effect compression of said carbon pile, a tubular sleeve member of ceramic material for receiving said carbon pile inwardly thereof, and a metallic radiator of resilient construction having an internal diameter normally less than that of said tubular member surrounding said tubular member in close heat transferring relation therewith, said radiator having a longitudinally extending slot therein and being expandable to receive said tubular member and to maintain said close heat transferring contact with said tubular member under temperature changes.

3. A carbon pile device comprising a solenoid, an armature for said solenoid, a carbon pile, means for transmitting pressure from said armature to effect compression of said carbon pile, a tubular member for receiving said carbon pile inwardly thereof, and a metallic radiator surrounding said tubular member in close heat transferring relation therewith, said radiator having deep fins therein of stepped width and the walls of each step being substantially parallel.

4. The method of making a pole piece for an electromagnetic device which comprises forming a groove in the face of and extending partially through a body of magnetic material leaving an integral section thereof, placing nonmagnetic material in said groove in firmly bonded relation with the surface of said groove, and thereafter removing material from the opposite face of said body of magnetic material beyond said integral section leaving two portions of magnetic material spaced from and held in accurate alignment with each other by an intervening section of said non-magnetic material.

5. The method of making a pole piece for an electro-magnetic device which comprises forming an annular groove in the face of and extending partially through a body of magnetic material leaving an integral section thereof, placing non-magnetic metallic material in said groove in firmly bonded relation with the surface of said groove, and thereafter removing material from the opposite face of said body of magnetic material beyond said integral section leaving two portions of magnetic material spaced radially from and held in accurate alignment with each other by an intervening section of said non-magnetic material.

6. In a carbon pile device, a carbon pile, a solenoid, a flat pole piece in magnetic relation with said solenoid, an armature assembly cooperating with said pole piece and including a flat armature plate, a spring hinge member fastened to said plate in substantially the plane of the face thereof, means for mounting said hinge member upon said pole piece with said pole piece forming a fulcrum for said hinge member, means on the opposite side of the hinge axis of said hinge member from said armature assembly for counterbalancing said assembly to compensate for vibrational effects in the plane normal to said

armature, and means for transmitting the pull of said armature to said carbon pile to effect compression thereof.

7. The method of forming a magnetic device including a core and a pole piece in accurate alignment therewith comprising forming a groove in the face of and extending partially through a body of magnetic material leaving an integral section thereof, placing non-magnetic material in said groove in firmly bonded relation with the surface of said groove, securing a core in assembled relation upon said body on the face thereof having said groove, and thereafter supporting said assembly from said core while removing material from the opposite face of said body to a depth beyond said groove leaving two spaced areas of magnetic material separated by said non-magnetic material and in predetermined accurate relation with said core.

8. The method of forming a magnetic structure including a core and a pole piece in accurate alignment therewith comprising forming a groove in the face of and extending partially through a body of magnetic material leaving an integral section thereof, placing non-magnetic material in said groove in firmly bonded relation with the surface of said groove, securing a core in assembled relation upon said body on the face thereof having said groove, and thereafter turning said assembly about the axis of said core while removing material from the opposite face of said body to a depth beyond said groove leaving two spaced areas of magnetic material separated by said non-magnetic material and in predetermined accurate relation with the axis of said core.

9. In a carbon pile device, a carbon pile, a solenoid, a flat pole piece in magnetic relation with said solenoid, an armature assembly cooperating with said pole piece and including a flat armature plate, a thin spring hinge member fastened to said plate, means for mounting said hinge member upon said pole piece with the edge of said pole piece forming a fulcrum for said hinge member, and means for applying a biasing pressure to said armature plate in substantially the plane of said hinge member in the same direction as the force developed by said solenoid to establish a minimum pressure condition within said pile.

10. In a carbon pile device, a carbon pile, a solenoid, a flat pole piece in magnetic relation with said solenoid, an armature assembly cooperating with said pole piece and including a flat armature plate, a spring hinge member fastened to said plate, means for mounting said hinge member upon said pole piece with said pole piece forming a fulcrum for said hinge member, means for applying a biasing pressure to said armature plate in substantially the plane of said hinge member and in the same direction as the force developed by said solenoid to establish a minimum pressure condition within said pile, and means for adjusting the point of application of said biasing pressure relative to said fulcrum to vary said minimum pressure condition.

11. In a carbon pile device, a carbon pile, a solenoid, corner posts forming part of the magnetic circuit of said solenoid, a pole piece mounted on said corner posts and having a magnetic gap in the face thereof, an armature assembly cooperating with said pole piece and including a flat armature plate, a spring hinge member secured to said plate, means for fastening said hinge member to a pair of said corner posts in position upon the face of said pole piece with said pole piece forming a fulcrum for said assembly.

12. In a carbon pile device, a carbon pile, a solenoid, corner posts forming part of the magnetic circuit of said solenoid, a pole piece mounted on said corner posts and having a magnetic gap in the face thereof, an armature assembly cooperating with said pole piece and including a flat armature plate, a spring hinge member secured to said plate, said armature plate having clearance with respect to a pair of said corner posts, and means for fastening said hinge member to said pair of corner posts in position upon the face of said pole piece for movement of said plate relative to said pole piece.

13. In a carbon pile device, a carbon pile, a core of magnetic material, a solenoid on said core, corner posts forming part of the magnetic circuit of said solenoid, a pole piece mounted on said corner posts and having a non-magnetic gap in the face thereof, an armature assembly cooperating with said pole piece and including a flat armature plate, a spring hinge member secured to the face of said plate adjacent said pole piece, said hinge member having spaced extensions adapted to be received in position on a pair of said corner posts, and means including said extensions for fastening said hinge member in position directly upon the face of said pole piece with said pole piece forming a fulcrum for said assembly.

14. In a carbon pile device, a carbon pile, a core of magnetic material, a solenoid on said core, corner posts forming part of the magnetic circuit of said solenoid, a pole piece mounted on said corner posts and having a non-magnetic gap in the face thereof, an armature assembly cooperating with said pole piece and including a flat armature plate, a spring hinge member secured to the face of said plate adjacent said pole piece, said hinge member having spaced extensions adapted to be received in position on a pair of said corner posts, means including said extensions for fastening said hinge member in position directly upon the face of said pole piece with said pole piece forming a fulcrum for said assembly, a groove formed in the outer surface of said plate, and resilient means engageable in said groove for applying a biasing pressure to said armature.

15. In a carbon pile device, a carbon pile, a core of magnetic material, a solenoid on said core, corner posts forming part of the magnetic circuit of said solenoid, a pole piece mounted on said corner posts and having a non-magnetic gap in the face thereof, an armature assembly cooperating with said pole piece and including a flat armature plate, a spring hinge member secured to the face of said plate adjacent said pole piece, said hinge member having spaced extensions adapted to be received in position on a pair of said corner posts, means including said extensions for fastening said hinge member in position directly upon the face of said pole piece with said pole piece forming a fulcrum for said assembly, and means mounted on said pair of corner posts for applying a biasing pressure to the outer surface of said plate.

16. In a carbon pile device, a carbon pile, a core of magnetic material, a solenoid on said core, corner posts forming part of the magnetic circuit of said solenoid, a pole piece mounted on said corner posts and having a non-magnetic gap in the face thereof, an armature assembly cooperating with said pole piece and including a flat armature plate, a spring hinge member secured to the face of said plate adjacent said pole piece, said hinge member having spaced extensions adapted to be received in position on a pair of said corner

posts, means including said extensions for fastening said hinge member in position directly upon the face of said pole piece with said pole piece forming a fulcrum for said assembly, and means mounted on said pair of corner posts for applying a biasing pressure to the outer surface of said plate, said groove having a curved surface providing for adjustable contact with said resilient means.

17. In a carbon pile device, a carbon pile, a core of magnetic material, a solenoid on said core, corner posts forming part of the magnetic circuit of said solenoid, a pole piece mounted on said corner posts and having a non-magnetic gap in the face thereof, an armature assembly cooperating with said pole piece and including a flat armature plate, a spring hinge member secured to the face of said plate adjacent said pole piece, said hinge member having spaced extensions adapted to be received in position on a pair of said corner posts, means including said extensions for fastening said hinge member in position directly upon the face of said pole piece with said pole piece forming a fulcrum for said assembly, a groove formed in the outer surface of said plate, resilient means engageable in said groove for applying a biasing pressure to said armature, and means for adjusting the point of application of said resilient means relative to said fulcrum to vary the biasing pressure on said armature.

18. In a carbon pile device, a solenoid, an armature for said solenoid, a carbon pile, a tubular member for receiving said carbon pile inwardly thereof, a magnetic circuit including a bottom plate, a core of magnetic material on which said solenoid is mounted having a portion projecting slidably through and beyond said bottom plate in the direction of said tubular member, said projecting portion having engagement with said tubular member for locating said member and said pile accurately with respect to said solenoid.

19. In a carbon pile device, a solenoid, a pole piece for said solenoid at one end thereof, an armature for cooperation with said pole piece, a carbon pile, a tubular member for receiving said carbon pile inwardly thereof, means for mounting said tubular member adjacent and in alignment with said solenoid at the opposite end thereof from said pole piece, a core for said solenoid, and means forming an outwardly extending projection on said core adapted to be received within said tubular member for locating said member and said carbon pile in accurate alignment with said core.

20. In a carbon pile device, a solenoid, a pole piece for said solenoid at one end thereof, an armature for cooperation with said pole piece, a carbon pile, a tubular member for receiving said carbon pile inwardly thereof, means for mounting said tubular member adjacent and in alignment with said solenoid at the opposite end thereof from said pole piece, a core for said solenoid, means forming an outwardly extending projection on said core adapted to be received within said tubular member for locating said member and said carbon pile in accurate alignment with said core, and an operating rod extending through said core from said armature and into said tubular member for transmitting pressure from said armature to said pile.

21. In a carbon pile device, a solenoid, an armature for said solenoid, a carbon pile, a tubular member for receiving said carbon pile inwardly thereof, a core of magnetic material on which said solenoid is mounted and extending axially

in the direction of said tubular member, means forming a projection on said core adapted to engage with said tubular member for locating said member and said pile accurately with respect to said solenoid, a contact member for making electrical contact at one end of said carbon pile, and means associated with said contact member and interfitting with said tubular member for locating said contact member in predetermined position with respect to said pile.

22. A magnetic device including a core and a pole piece in the form of a body of magnetic material including a radially inner portion and a radially outer portion separated therefrom by an intermediate annular portion of non-magnetic material, said pole piece being secured to said core and being faced off to form a uniformly plane working face extending across said inner and outer magnetic portions and said intermediate non-magnetic portion in accurate perpendicular relation to the axis of said core.

23. The method of forming a magnetic device including a core and a pole piece in the form of a body of magnetic material including a radially inner portion and a radially outer portion separated therefrom by an intermediate annular portion of non-magnetic material which comprises the steps of securing said pole piece to said core, and thereafter facing off said pole piece including the surface of said inner and outer magnetic portions and said intermediate non-magnetic portion to form a uniformly plane working face in accurate perpendicular relation to the axis of said core.

24. A magnetic device including a core and a pole piece in the form of a body of magnetic material including a radially inner portion and a radially outer portion separated therefrom by an intermediate annular portion of non-magnetic

material having a tapered cross section increasing in the direction away from a working face thereof, said pole piece being secured to said core and being faced off to form a uniformly plane working face extending across said inner and outer magnetic portions and said intermediate non-magnetic portions in accurate perpendicular relation to the axis of said core, the depth of the facing cut determining the minimum extent of the non-magnetic gap between said inner and outer portions.

25. A magnetic device including a core and a pole piece in the form of a body of magnetic material including a radially inner portion and a radially outer portion separated therefrom by an intermediate annular portion of non-magnetic material having a tapered cross section increasing in the direction away from a working face thereof, said pole piece being secured to said core and being faced off to form a uniformly plane working face extending across said inner and outer magnetic portions and said intermediate non-magnetic portions in accurate perpendicular relation to the axis of said core, the depth of said facing cut determining the minimum amount of non-magnetic gap between said inner and outer portions.
